SHIP MODEL WALL PLAQUE

Francis R. Nartowicz, 204 Fort Worth St.,
Hampton, Va. 23369

Filed Aug. 20, 1971, Ser. No. 173,741

Term of patent 14 years

Int. Cl. D11—02

U.S. Cl. D29—23 A

FIG.

FIG. 6.

FIG. 1 is a front elevational view of a ship model wall plaque showing my new design;

FIG. 2 is a top plan view thereof;

FIG. 3 is a bottom plan view;

FIG. 4 is a side elevational view taken from the right of FIG. 1;

FIG. 5 is a side elevational view taken from the left of FIG. 1; and

FIG. 6 is an enlarged fragmentary front elevational view thereof.

I claim:

The ornamental design for a ship model wall plaque, as shown.
